UNITED STATES PATENT OFFICE.

JOHN EWIN GLASS, OF MARION, KENTUCKY.

MAIL-EXCHANGE DEVICE.

1,379,974.

Specification of Letters Patent. Patented May 31, 1921.

Application filed February 4, 1919. Serial No. 274,947.

To all whom it may concern:

Be it known that I, JOHN E. GLASS, a citizen of the United States, residing at Marion, in the county of Crittenden and State of Kentucky, have invented a new and useful Mail-Exchange Device, of which the following is a specification.

This invention is a device of the type employed for transferring mail sacks and the like to and from moving railway cars or trains.

One object of the invention is to provide a device of simple construction by means of which mail matter may be safely transferred to or from a moving car, and accurate coöperation of the train and station device assured. A further object is to provide a simple train device which may be applied to any car having side openings. A further object is to provide means by which the train device may be selectively supported and positioned so that it may be adjusted to the direction of travel of the car. A further object is to provide a simple station device capable of receiving mail matter from and delivering other mail matter to a moving car without danger of injuring persons in the vicinity. A further object is to provide a station device capable of protecting the mail matter from the weather while it is in position to be taken up by the train device.

The invention will be hereinafter fully set forth and particularly pointed out in the claims.

In the accompanying drawing:—

Figure 1 is a top plan view illustrating the invention. Fig. 2 is an enlarged perspective view of the train device. Fig. 3 is a view of the device from the inside of the car. Fig. 4 is a longitudinal section illustrating the station device.

Referring to the drawing, 10 designates a railway track and 11 uprights stationed contiguous to the track and connected by a cross-piece 12. Hinged to one of the uprights 11, is a supporting panel 13, provided with a latch 14 positioned to engage a suitable keeper on the other upright 11. Supported by the panel 13 is a box-like receptacle 15 divided into two compartments 16, 17 by a partition wall 18. The top and bottom walls of the compartments are slotted longitudinally as indicated at 19, the slots being flared at the extremities of the receptacle, as shown.

Supported by the panel 13 so as to overhang the receptacle 15 is an upper carrier plate 20, which extends longitudinally of the receptacle and is slotted at the ends as 21, the slotted portions registering with the slots 19 in the top wall of the receptacle. A similar lower carrier plate 22 is supported beneath the receptacle and provided with slots 19 in the bottom wall of the receptacle. To protect the receptacle and its contents from the weather as much as possible, the panel 13 is provided with a roof or cover 24, which overhangs the receptacle.

The car device is mounted upon a suitable car 25 of any preferred structure and comprises a vertical body 26, provided at its ends with integral angularly disposed parallel arms 27 provided at their extremities with keepers 28, said keepers being provided with longitudinal slots 29. The body 26 is suitably braced and attached to a rod-like supporting portion 30, having its ends shaped to engage upper and lower keepers 31 and 32, whereby the train device may swing in and out of the car. The upper keeper 31 is pivoted to the door frame so that it may be moved to permit of the placing of the train device into position. There is a set of upper and lower keepers 31, 32 on each side of the car door so that the body 26 may be selectively placed in engagement with either set to conform to the direction of travel of the car.

In practice, the mail sack "a" is to be delivered from the car to the station and the mail sack "b" to be taken up by the car without interfering with the movement of the latter. The sacks are provided with flexible members 33 capable of engaging the slots 29 of the keepers 28 and the slots 21 and 23 of the carrier plates. The sack "a" which is to be delivered is engaged with those slots 29 of the keepers 28, which are at the rearmost point with respect to the direction of travel of the car. In the illustration selected for the drawing the sack "a" is to be delivered into the compartment 16 and the sack "b" is supported by the carrier plates 21, 22 with flexible members 33 passed through the slots 19 and engaging the slots of the carrier plates. As the car approaches the receptacle 15, the train device is swung outwardly until the slots 29 register with the slots 19. As the train travels the movement of the sack will be arrested.

by the partition wall 18, the arms 27 passing above and below the receptacle respectively. As the car continues in its travel the forwardly disposed slots 29 of the keepers 28 engage the flexible members 33 of the sack "b" with sufficient force to wedge the said flexible members into the slots, therefore holding the sack with sufficient tenacity to enable it to be swung back into the car.

Should it be desired to effect the operation with a car traveling in the opposite direction, the train device 26 is transferred to the other side of the door.

Having thus explained the nature of the invention and described an operative manner of constructing and using the same, although without attempting to set forth all of the forms in which it may be made, or all of the forms of its use, what is claimed is:—

1. A mail transfer device comprising a train member provided with a body portion having integral angularly disposed carrier arms, a supporting member attached to said body portion throughout the length of the latter, retaining means pivotally engaging the ends of said supporting member, whereby the train member may swing on a vertical axis, sack-engaging members on said

arms extending transversely thereof, and means coöperating with the train member 30 for receiving mail matter from and delivering other mail matter to the same.

2. A mail transfer device comprising a body portion provided with angularly disposed carrier arms, a supporting portion attached thereto, sack engaging members attached to the extremities of said arms and disposed transversely thereof and keepers in which the ends of said supporting portion are journaled, one of said keepers being 40 removable to permit disengagement and removal of said supporting member.

3. A mail transfer device comprising a body portion provided with angularly disposed carrier arms, a supporting portion 45 attached thereto, sack engaging members attached to the extremities of said arms and disposed transversely thereof and keepers in which the ends of said supporting portion are journaled, one of said keepers 50 being pivoted to permit of its disengagement with said supporting portion.

In testimony whereof I have hereunto set my hand.

JOHN EWIN GLASS.
